UNITED STATES PATENT OFFICE.

JOSEPH ABETZ, OF NEW BRITAIN, CONNECTICUT.

CREEPER.

Application filed September 11, 1925. Serial No. 55,860.

My invention relates to improvements in creepers, of the form that is applied to the heel of a shoe or other footwear for preventing slipping under conditions of icy and slippery going for foot travelers and the object of my improvement is to produce a creeper that, while primarily, as shown, is adapted to be applied to the heels of rubber overshoes and taking advantage for 5 curing a holding effect of a rounded, rolled, or curled edge that is more or less common thereon, is adapted to be applied to leather heels by suitable changes in details, particularly as to height of the inwardly overhanging flanges that are provided, and in 10 which means of convenient form are provided for adjustment for a particular size of shoe.

In the accompanying drawings: —

20 Figure 1 is a side elevation of my improved creeper as applied to a rubber heel.

Figure 2 is a rear elevation of the same.

Figure 3 is a plan view of the creeper.

25 Figure 4 is a sectional view on the line 4—4 of Fig. 3.

Figure 5 is a bottom view of the front end portion.

30 Figure 6 is a bottom view of a modification, showing a different form of teeth, made integral with the plates.

Figure 7 is a fragmentary side view of a few of the teeth shown in Fig. 6 with the adjacent parts.

35 My improved creeper comprises a pair of mating plates 10 that have overlapping ends 11 at the rear and that are held together at the front by means of a cross-piece or tie-plate 12 and which are provided with a set of teeth 13 that project downwardly from 40 the under faces for contacting with the ice in walking.

As shown, the creeper is applied to the heel 14 of a rubber overshoe and particularly as will be described has means for being held in place by engaging with the bead or rolled flange 15 of said heel 14 and which bulges outwardly relatively to the adjacent face of the rubber.

45 The plates 10 each comprise a flat plate-like body 16 that extends longitudinally and to which the teeth or prongs 13 are attached by screw-thread engagement with the walls of the openings 17 that are distributed over said body 16.

50 At the lateral edge of the body 16 in each case there is an upstanding flange 18 that

has the top edge 19 turned inwardly so as to overhang the inner space, the structure of said flange 18 being such that it will substantially enclose the opposed bead 15 on the 60 rubber heel 14. To this end the flanged structure composed of the flange proper 18 and the overhanging portion 19 at the top edge, and that serves as the supporting means in cooperation with the bead on the rubber or the like is of appreciable extent 65 in the longitudinal direction at the sides and also extends in curved form around the rear, terminating, as shown, adjacent the overlapping connecting ends 11 of said 70 flange proper 18.

The overlapping ends 11 at the rear are extensions of the flanges 18. The inner of 75 said overlapping ends 11 has a plurality of screw-threaded openings 20 for the locking bolt 21 and the outer thereof has a laterally directed slot 22 for the body of said bolt 21.

At the front end of each of the plates 10 there may be a lug 23, at the upper corner, 80 and that has an opening 24 for a cord, the two cords being tied together over the foot of the wearer as an emergency measure.

The tie 12 extends across the front ends 85 of the plates 10, in contact with the bottom faces thereof, and is held in place by means of screws 26 that extend upwardly from the bottom, through slots 27 in the tie, and that engage with screw-threaded holes 28 in 90 the plates 10.

As shown, there are two slots 27 and two screws 26 at each end 29 of the tie 12, wherefore, the plate designated as the tie 12 operates not only as a simple tie, to sustain 95 longitudinal strain, but also serves to unite the plates 10 into a substantially unitary plate structure as to the mechanical features.

The use of the screws and the slotted structures shown and described permits of 100 adjusting the plate structures 10 so as to fit a particular shoe. Generally, the adjustment obtained will produce a setting such that the creeper can be readily slipped on and off the heel by the use of a small amount of force and will be held snugly in place without the use of the cords 25.

In lieu of the screw-threaded teeth or prongs 13 there may be used teeth 13^a that are formed integral with the body 16^a of 110 the plate 10^a as shown in Fig. 6 by slitting the material along two sides to form a point

30 and bending the points 30 downwardly. The screw-threaded teeth or prongs 13 are removable and interchangeable. Fixedly secured teeth may be provided in lieu of the teeth 13 that are held in place by riveting.

In order to permit of the use of relatively thin sheet metal and at the same time provide for a sufficient number of screw-threads 10 screws or bolts, particularly the screws or bolts that are used to hold the parts at a certain setting or adjustment, comprising 21 for the rear and 26 for the cross-plate, the cooperating screw-threaded holes are 15 made relatively elongated by forcing material that is at the borders of the holes forwardly so as to extend beyond the adjacent face of the plate or sheet.

The structure shown and described is 20 adapted for use with rubber overshoes having a laterally projecting or overhanging border or bead at the outer corner or edge such as to be adapted to be substantially enclosed by the upstanding flange 18 and the 25 inwardly overhanging top edge or lip 19 that is provided thereon.

The structure is also adapted for use with leather heels or with heels of leather that are provided with a rubber heel of common form by providing a groove for the edge 30 or lip 19. Such a groove is easily made by a tool in the form of a revolving cutter and which is commonly found in the equipment of a modern shoe repair shop.

I claim as my invention:—

35 In a creeper for use with a rubber shoe or the like having an outwardly projecting bead bordering the heel structure, a pair of mating plates having opposed and adjacent plate-like bodies, flanges projecting upwardly from the outer edges of said plates, extensions of said flanges extending around at the rear, overlapping, and provided with connecting means, the top edges of said flanges being curled over inwardly for co-operating with the adjacent portions of the flanges for enclosing said bead for serving as holding means, and a bridge plate connected along the lower faces of the forward ends of said plate-like bodies.

JOSEPH ABETZ.
